United States Patent Office.

JACOB W. HILL, OF JEFFERSON, AND THOMAS ROBERTS, OF PANORA, IOWA.

Letters Patent No. 100,149, dated February 22, 1870.

ROTARY STEAM-ENGINE.

The Schedule referred to in these Letters Patent and making part of the same.

To all whom it may concern:

Be it known that we, JACOB W. HILL, of Jefferson, Greene county, and THOMAS ROBERTS, of Panora, in the county of Guthrie, and State of Iowa, have invented a new and valuable Improvement in Rotary Steam-Engines; and we do hereby declare that the following is a full, clear, and exact description of the construction and operation of the same, reference being had to the annexed drawings making a part of this specification, and to the letters and figures of reference marked thereon.

Figure 1 of the drawings is a representation of my invention, with one wall of the cylinder removed.

Figure 2 is a representation of the removed wall.

Figures 3, 4, 5, and 6 are details.

Our invention relates to rotary engines, and consists, mainly, in the construction and novel arrangement of the valves, piston-blocks, and steam-ports, designed to lessen the complexity and to enhance the efficiency thereof.

The letter A of the drawings designates the cylindrical case of the engine, arranged with suitable packing-rings between its inner walls and the rotating cylinder.

B B designate the valves, arranged diametrically opposite to each other, and consisting each of a double gate, formed of two plates hinged to the cylinder walls, and arranged in such a manner that, when closed by the action of suitable springs, a a, they form a salient angle in the direction of movement of the piston-blocks b b, indicated by the arrow in the drawings.

These valve-gates are opened by the action of the wedge-shaped piston-blocks b b in passing through them, recesses being formed in the walls of the case to receive the hinged plates when the gates are opened.

In order to enable these valve-gates to adjust themselves to the curve of the cylindrical walls of the case A and rotating wheel C, in their different positions, when open and shut, spring packing-plates, c c, are introduced in slots in each curved side, and so arranged that they will press outward against the cylindrical walls, and thereby render the valves always steam-tight.

The exhaust-ports are designated by the letters e e. The steam-ports marked v v open into the curved slots z z formed in the plane side m of the wheel C, near the outer edge thereof, and each about ninety degrees of the circle in length.

These slots open into the steam-chamber E, each just in rear of its corresponding piston-block.

The plane face m of the rotating wheel is ground smooth between the ends of the steam-slots z z, fitting the openings of the steam-pipes closely, and operating to cut off the steam at the proper point of the circuit. The expansive force of the steam operating upon the salient side of the valve-gate keeps it tightly closed until the steam-port passes beyond the end of the slot, and the steam is cut off.

What we claim as our invention, and desire to secure by Letters Patent, is—

1. In combination with the shaft-wheel of a rotary steam-engine, the wedge-shaped piston-blocks b b, when constructed and arranged to operate as specified.

2. The valve-gates B B, salient in the direction of rotation, provided with the expanding packing-plates c c, and operated by the springs a a, and the direct action of the wedge-shaped piston-blocks b b, as specified.

3. In combination with the valve-gates B B, the rotating wheel C, having the slots z z and cut-off face m m, when constructed and arranged to operate substantially as herein described.

4. The rotary steam-engine, herein described, provided with hinged valve-gates B, rotating wheel C, having wedge-shaped piston-blocks b b, steam slots z z, and cut-off face m and exhaust-ports e e, arranged to be always open, when constructed and operated substantially as herein set forth.

In testimony that we claim the above, we have hereunto subscribed our names in the presence of two witnesses.

JACOB W. HILL.
THOMAS ROBERTS.
